UNITED STATES PATENT OFFICE.

BION B. FARNHAM, OF NEW YORK, N. Y.

EXPANSIBLE PULLEY.

SPECIFICATION forming part of Letters Patent No. 652,763, dated July 3, 1900.

Application filed May 4, 1900. Serial No. 15,481. (No model.)

To all whom it may concern:

Be it known that I, BION B. FARNHAM, a citizen of the United States, residing at New York, (Castleton,) in the State of New York, have 5 invented certain new and useful Improvements in Expansible Pulleys; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

15 This invention relates to expansible pulleys; and my invention is so arranged as to render the expansion and contraction thereof easy and rapid.

In the drawings, Figure 1 shows a longitudinal sectional view of my pulley in operative construction; Fig. 2, an elevation of the retaining-plate; Fig. 3, an elevation of the expansion-plate; Fig. 4, an elevation of the clamping-plate, and Fig. 5 an end view of the 25 cap revolvably set upon one of the ends of the shafting; Fig. 6, a sectional elevation of one side of my pulley, enlarged to clearly show the parts.

The numeral 1 indicates a tubular shaft 30 having openings 2 through its walls in order that the parts occupying the interior may be seen and easily arranged and repaired. In the shaft 1 I preferably set circular blocks 3, with openings in them and arranged to act 35 as boxes to support and in which the rods 6 and 7 may rotate. While I prefer this method of making the rods 6 and 7 rotatable, I do not confine myself thereto, as any other method may be used that may be desired. The rods 40 6 and 7 are prevented from having an endwise thrust preferably by means of washers 17, but any other means may be used. The rods 6 and 7 are each threaded right and left—*i. e.*, that portion of rod 6 resting in the tubular shaft to the left of the central block is threaded left hand, as at 6", and that portion thereof resting in the shaft to the right of said block is threaded right hand, as at 6', while that portion of rod 7 resting in the shaft 45 to the left of the central block is threaded right hand, as at 7', while that portion resting in the shaft to the left of said block is

threaded left hand, as at 7". Rod 6 will be seen to pass through a nut 11, the rod-threading meshing with appropriate threading in 55 each of said nuts. These nuts have shanks which pass through the openings 2 in shaft 1, and their ends are fixed to clamping-plate 12 in any well-known manner, but preferably by threaded bolts or screws. Rod 7 has similar nuts 11' thereon, their shanks being attached to spreading-plate 13. Their shanks pass through the openings 2 in the shaft 1 precisely as do those shown at 11 on rod 6. On the left-hand end of the shaft 1 is revolvably set a cap 4, with an opening in its outer 60 end and having the circular edge of the opening toothed, as seen at 5 in Fig. 5. Through this opening both of the rods protrude, and on each rod is set a small gear 8 and 9, arranged to be moved lengthwise on the shafts, so as to be thrown in and out of gear when desired, and to prevent their being revolvably on the rods they are fitted to slide over a feather 10, which is shown only on rod 6, that 65 on rod 7 being on the rear side of the rod. Both these small gear mesh with teeth 5 on the revolvably set cap 4 when they mesh with each other; but when either of them is slid outward on its respective rod, as is gear 8 on rod 70 6, then but one of them (gear 9) meshes with teeth 5. This is arranged so that when it is desirable to move clamping-plate 12 independent of the spreading-plate 13 it may be done, which allows of making plate 12 fully 75 and completely clamp arms 15 in secure position. Clamping-plate 12 has slots 12' and is fixed upon the shaft 1 to slide laterally thereon, but not to rotate on the shaft. Spreading-plate 13 is likewise fixed upon the shaft 1 80 and is preferably a solid plate having a beveled edge. Retaining-plates 14 are immovably affixed to the shaft and have slots 13', and between retaining-plates 14 rests the 85 segmental pulley-block 16, each of the segments 90 thereof having a downwardly-sloping arm 15, which passes through one of the slots 13', rests on the beveled edge of spreading-plate 13, and passes through one of the slots 12' in clamping-plate 12.

100 The operation is as follows: Gear 8 being slid along the rod 6 until it meshes with teeth 5 on cap 4 and with the gear 9 and the cap 4 being turned or rotated in one direction

clamping-plates 12 and spreading-plates 13 will move outward from retaining-plates 14, and as arms 15 slide over or upon the beveled edge of spreading-plates 13 segments 16 will be compelled to rise between plates 14 and increase the diameter of the segmental pulley. When cap 4 is turned oppositely, clamping-plates 12 and spreading-plates 13 will approach retaining-plates 14 and the segments 16 will fall between plates 14 and decrease the diameter of the pulley. When it is desired to operate clamping-plate 12 alone, gear 8 is left to mesh with teeth 5 on cap 4; while gear 9 is thrown out of mesh by sliding 15 it along the rod 7, and by reversing the positions of the gears 8 and 9 the spreading-plate 13 may be moved without moving plate 12. It will be evident to those skilled in the art that plate 12 may be moved in other ways 20 and by other means than I have shown, and I show the way seen in the drawings only as my preferred method, while I do not confine myself thereto.

While I have not shown any particular 25 manner of rotating cap 4 except by hand-power, it may be made to rotate by means of a belt passed around cap 4 or by gearing it to a power-operated shaft or otherwise, as the circumstances may demand. By forming 30 sprockets on its periphery and passing a suitable chain over it, so as to operate with said sprockets, the chain forming a chain belt, the cap 4 may be operated by drawing on the chain. I have used this method in some cases 35 and find it to operate well. By use of clamping-plate 12 with its inwardly-projecting and angular flange I am enabled to do away with all set-screws and gibbs, such as were shown and described in my patent dated July 40 10, 1894, and numbered 522,658, and I am enabled to make a much better and secure clamp upon the arms 15, and by use of the two threaded rods 6 and 7 inside the tubular shaft and arranged practically as shown I am 45 enabled to better and easier operate the spreading and clamping plates, and therein

have greatly improved upon my invention shown and described in the patent hereinbefore mentioned.

Having described my invention, what I claim is—

1. In a segmental expansible pulley having projecting arms connected to the segments, a tubular shaft, spreading-plates, clamping-plates and retaining-plates arranged upon said shaft, the spreading and clamping plates arranged to be thrust lengthwise on said shaft, and a plurality of threaded rods inside said shaft, the threading being arranged to move nuts outwardly and inwardly on said shaft in unison, said nuts being fixed respectively to the clamping-plates and to the spreading-plates, the rods having means whereby they may be revolved irrespective of the revolutions of the shaft substantially as described.

2. In a segmental expansible pulley having projecting arms connected to the segments, a tubular shaft, and spreading-plates, clamping-plates and retaining-plates arranged upon the shaft, the spreading and the clamping plates being arranged to have lateral thrust along the shaft, and a plurality of threaded rods in said tubular shaft and nuts on said rods, some of said nuts being affixed to the spreading-plates and their threads meshing with the threads on one of the rods, and other of said nuts being affixed to the clamping-plates and their threads meshing with those on the other rod in order that the said spreading and the clamping plates may be moved laterally along said tubular shaft and clamp the arms of the segments, and means whereby the threaded rods may be rotated separately or collectively, all combined substantially as described.

In testimony whereof I affix my signature in presence of two witnesses.

BION B. FARNHAM.
